UNITED STATES PATENT OFFICE.

FRANCIS H. BROWN, OF PHILADELPHIA, PENNSYLVANIA, ASSIGNOR TO JOHN M. HOPWOOD, OF PITTSBURGH, PENNSYLVANIA.

REGULATING COMBUSTION IN FURNACES.

1,338,901.

Specification of Letters Patent.

Patented May 4, 1920.

Substitute for application Serial No. 184,261, filed August 3, 1917. This application filed February 12, 1920. Serial No. 358,108.

To all whom it may concern:

Be it known that I, FRANCIS H. BROWN, residing at Philadelphia, in the county of Philadelphia and State of Pennsylvania, a citizen of the United States, have invented or discovered certain new and useful Improvements in Regulating Combustion in Furnaces, of which improvements the following is a specification.

10 The invention described herein consists, generally stated, in controlling the flow of products of combustion from a fire box or furnace of a boiler by and in accordance with the flow of steam from the boiler and 15 controlling the feed of fuel and the flow of air to maintain combustion by and in accordance with the changes of pressure in the fire box or furnace, resulting from the controlled escape of the products of combustion from the furnace.

20 The invention also consists in controlling the flow of feed water to the boiler by and in accordance with the rate of flow of steam from the boiler. The invention is hereinabove more fully described and claimed.

25 In the accompanying drawing forming a part of this specification, is shown a diagrammatic view of a boiler and its setting and having applied thereto apparatus and 30 appliances suitable for the practice of the invention.

35 It will be understood that the method hereinabove described may be practised with any type or construction of boiler and furnace, and that although the apparatus and appliances shown and described herein are well adapted to the practice of the method, any other suitable construction may be employed.

40 In the practice of the invention, suitable means are employed whereby the difference between the static pressure of steam flowing from the boiler and the static pressure plus the pressure due to the velocity of flow of 45 the steam, or minus the drop of pressure due to the flow of steam through an orifice less than the diameter of the steam pipe, is utilized for producing motion which in turn is utilized for regulating the pressure of 50 gases in the fire box or furnace. Suitable means for effecting these objects consist of a Pitot tube 1 arranged in the steam pipe 2 leading to the engine 3. The nozzles 4 and

5 of this tube are connected by pipes 6 and 7 on opposite sides of the diaphragm of a 55 diaphragm motor 9. This diaphragm is adjustably connected by an arm 10 to a pivotally mounted frame 11 and on the frame is pivotally mounted a bell crank lever 12 having an arm connected to the movable 60 member of a valve mechanism 13, of any suitable construction, and the other arm connected by a rod 14 to a pivotally mounted standard 15. A shoe, pivotally connected to the standard so engages an angle 65 rod 12, carried by the frame 18, as to permit of the angular adjustment of the rod. The frame 18 is secured to a rod 19 connected by an arm 20 to the piston rod of a fluid pressure cylinder 21. This compensating 70 motor mechanism is more fully described and shown in application filed of even date herewith, Serial No. 358,107.

In the operation of this mechanism, a movement of the diaphragm of motor 9 will 75 shift the frame 11 and the movable member of the valve mechanism 13 connected to said frame, so as to permit of the flow of fluid under pressure through one of the pipes 22 or 23 to the end of the cylinder 21 and the 80 escape of fluid from the opposite end of the cylinder. As the piston of the cylinder is moved, the angle rod 17 will be shifted and by reason of its inclination will rock the standard 15. As the latter is connected to 85 the bell crank lever 12, the latter will be shifted and thereby move the movable member of the valve mechanism 13 in a direction opposite that imparted by the movement of the frame 11, thereby cutting off the flow 90 of fluid under pressure to and from the cylinder 21.

The piston rod 25 of the cylinder 21 is connected by any suitable means to the damper 26 in the conduit through which 95 products of combustion flow from the fire box or furnace 27 to a stack. In the construction shown, a cord or chain 28 is connected to the rod 25 and passing around a suitable guide pulley, is wound two or more 100 times around the drum 29 on the shaft of the damper 26 and is connected to a counter balancing weight.

In case of an increase in the rate of flow of steam through the pipe 2, the mechanism 105 hereinbefore described will be so operated as

to open the damper 26 to an extent proportional to the increase in the rate of flow of steam and a further increase in flow of steam will cause a further opening of the 5 damper. On the other hand, if the rate of flow of steam is decreased, the described mechanism will be so operated as to close or permit the closure of the damper to an extent proportional to such decreased flow.

10 The adjustment of the damper will permit a greater or less quantity of gases to escape from the fire box 27 and thereby diminish or increase the pressure within the fire box and by means of suitable appliances the 15 variations in pressure will cause a proportional but reverse adjustment in the flow of air through the bed of fuel, *i. e.*, an increase of pressure in the fire box will be followed by a reduction in the feed of air and a reduction 20 of pressure in the fire box will bring about an increase in the quantity of air supplied.

A convenient means for controlling the feed of air to the fire box as shown and described in Letters Patent No. 1,150,097, dated August 17, 1915, and diagrammatically shown in A herein.

In the operation of the pressure actuated mechanism A, due to changes of pressure in 30 the fire box, fluid is admitted to one or the other end of a cylinder 31, thereby causing an up and down movement of the piston rod 32. This rod is connected to one end of a flexible cord or chain 33 passing around 35 guide pulleys 34 and two or more times around a drum 35 on the shaft of the damper 36 arranged in the conduit 37 extending from the uniformly operating blower 38 to the ash pit of the fire box. In the arrangement 40 shown, the damper is moved in one direction by a pull exerted on the operation of the pressure actuated mechanism and in the opposite direction by a weight 39, the operation of the pressure actuated mechanism 45 being reversed. While the construction and combination of appliances herein shown and described are well adapted for feeding fuel and controlling the feed of air to the ash pit, the invention claimed herein 50 is not limited to such specific constructions and combinations, as other means for supplying air and fuel as required by changes of pressure conditions in the fire box, due to changing in the rate of flow of steam from 55 the boiler, will readily suggest themselves to those skilled in the art.

The supply of fuel is also controlled by 60 changes of pressure in the fire chamber putting into operation the pressure actuated mechanism A. As shown, the lower end of the piston rod 32 is connected by a lever 43 to the rod 44 of the movable member of the valve mechanism 45, which is connected by a pipe 46 to the boiler or other suitable 65 source of fluid under pressure, and by the

pipe 47 to the motor of a stoking mechanism 48 which may be of any suitable type or construction. Connection of the piston rod 32 to the valve mechanism 45 is so arranged that the movement of the rod 32 to 70 permit of the admission of a greater flow of air to the ash pit will so shift the movable member of the valve mechanism 45 as will result in an acceleration of the stoking mechanism and an increased feed of fuel to the 75 fire box.

As hereinbefore described, provision is made for controlling combustion in accordance with the steam requirements, combustion increasing or decreasing by changing 80 the supply of fuel, and air for combustion as the demand for steam varies. Changes in the rate of flow of steam not only necessitates changes in combustion but also an adjustment of the feed of water to the boiler, 85 and to attain the best results, the feed of water should be proportional to the consumption of steam. To this end, the piston rod 25 of the cylinder 21 is connected to a valve 49 in the feed water pipe 50. A suitable connection consists in a cord or chain 41 having one end connected to the cord or chain 33 and its opposite end to an arm of the valve 49. The valve may be shifted in a direction opposite that imparted by the piston in cylinder 21 by a weight 42.

It will be obvious to those skilled in the art that the pressure actuated device can be connected to means employed and well known in the art for regulating the flow of 100 liquid or gaseous fuel to the furnace and also for the air necessary for the proper combustion of such fuel.

This application is filed in place of application Serial No. 184,261, filed August 3, 105 1917, but became abandoned February 23, 1919.

I claim herein as my invention:

1. The method herein described of controlling combustion in furnaces of boilers 110 which consists in changing the rate of discharge of gases from the furnace by and in accordance with the flow of steam from the boiler, and regulating the feed of fuel and the flow of air into the furnace by and in accordance with variations of pressure in the furnace.

2. The method herein described which consists in changing the rate of discharge of gases from the furnace of a boiler and the 120 feed of water to the boiler by and in accordance with the flow of steam from the boiler and regulating the feed of fuel to the furnace by and in accordance with changes of pressure in the furnace.

3. The method herein described which consists in changing the feed of water to the boiler by and in accordance with the rate of flow of steam from the boiler and adjusting the flow of air into the furnace by and in 130

accordance with the changes of pressure in the furnace.

4. The method herein described which consists in changing the rate of discharge of 5 gases from the furnace of a boiler and feed of water to the boiler, by and in accordance with the rate of flow of steam from the

boiler and regulating the feed of fuel and the supply of air for combustion in accordance with changes of pressure in the furnace. 10

In testimony whereof I have hereunto set my hand.

FRANCIS H. BROWN.
